SHAVING PREPARATION

George D. Gettemuller, Bridgeton, N. J., and
Samuel L. Goldheim, Baltimore, Md.No Drawing. Application September 15, 1933,
Serial No. 689,566

1 Claim. (Cl. 87—5)

The improved shaving preparation comprising the present invention possesses among other features the advantage that no lathering is required. The present and almost universal practice in shaving consists in applying to the area of the skin to be shaved a soapy emulsion and working up on this area a lather or foam of soap and water. This use of lather in shaving provides a material which combines the properties of softening the hair and furnishes a degree of mechanical support for the same so that the hair will remain erect in order that it may be cut by the razor edge. Preparations of this type are ordinarily sold in the form of a dry cake or in the form of cream which may be applied to the face and which when combined with water forms a lather. Such preparations therefore belong to the lather type. In the use of these preparations it has been found that although they may lather freely, the lather is not permanent and soon dries, requiring additional wetting of the face and a further working up of the lather.

Comparatively recently emulsions of the oil and water type have been introduced to supersede the lather type of shaving preparation. These preparations may be classified as the latherless type inasmuch as no foam or lather is produced on the face. These preparations compare favorably with the lather type of preparations in that they possess as great a softening action and an even greater mechanical supporting power.

It is to this class or type of shaving preparation that the present invention pertains.

Shavers of long experience have found that the passage of the razor edge across the face is invariably accompanied by the production of superficial cutaneous abrasions of the skin. These abrasions are more often than not invisible, but result in subsequent irritation of the skin, especially since the alkaline properties of soap are irritating to the abraded surfaces. Many of the oil and water type of latherless emollients employed in shaving contain soap and other alkaline substances which are similarly irritating to the abraded surfaces. The use of these alkaline substances, whether they be of the lathering type or of the latherless type, is frequently accompanied by irritation of the skin which persists after the shaving operation is completed. Indeed, most experienced shavers have been obliged to resort to the use of such emollient as lotions and skin balms which are commonly referred to as after shaving lotions, and which are employed for alleviating the abraded surfaces of the skin.

The improved shaving preparation overcomes

the above mentioned objections by modifying the use of such alkaline substances and by incorporating therein a plurality of substances having local anesthetic and healing properties.

The following formula gives the preferred composition, but it is to be distinctly understood that the proportions of the ingredients may be varied slightly in either direction without destroying the beneficial properties of the resulting emulsion. It is also to be understood that certain of the constituents employed may be dispensed with and substances having similar properties may be substituted in their stead, as will be more fully described hereinafter. The formula is as follows:

	Grams
Stearic acid (C. P.)	11
Lanolin (hydr. 20% water)	10
Cocoanut oil	.3
Ammonium hydroxide (conc.)	1.35
Paraffin wax	6
Spermaceti wax	2
Boric acid	1.5
Water	75
Menthol	25
Camphor	
Perfume, such as	
Oil of bergamot	
Oil of almonds	
Oil of rose geranium	30
Oil of peppermint, etc.	

or the preferred formula may be varied as follows:

	Percent
Stearic acid	9-12
Lanolin	8-12
Coconut oil	.2-.4
Ammonium hydroxide	1-2
Paraffin wax	4-6
Spermaceti wax	1-2
Boric acid	1-2
Water	60-75

In the above mentioned formula, menthol and camphor are incorporated in suitable amounts adapted for the most pleasing effect. Likewise, the perfumed substances may be added with discretion.

In the preferred method of preparing the above mentioned formula the stearic acid and hydrous lanolin containing 20% water, together with the cocoanut oil, are melted together and to this mixture is added the concentrated ammonium hydroxide, which contains approximately 25% am-

monia. The waxes are then added and heating is continued until the entire mixture is liquefied. The resulting mixture is subsequently removed from the heat and a warm solution of the boric acid in approximately 75 g. of water is added while continuously stirring. At this point or at any point previously, the menthol, camphor and selected perfumes are added in amounts which give the most pleasing effect.

It is to be distinctly understood, however, that the various ingredients comprising the present invention may be mixed in any desired manner, for example, the stearic acid, the hydrous lanolin and the waxes may be previously mixed and melted and ammonium hydroxide and other substances subsequently added. Irrespective, however, of these details in the preparation of the compound the essential features of the invention are not destroyed.

The mixture is then violently stirred or whipped until cold and the final resulting product consists in a white creamy preparation free from grease.

In the preparation of the mixture the stearic acid serves as an excellent base. The hydrous lanolin blends well into the mixture and serves as an emollient for softening the hair. This lanolin is also readily absorbed by the skin and carries with it into the skin the antiseptic boric acid.

The cocoanut oil gives a smooth texture to the preparation and serves as a lubricant for the razor blade. The ammonia reacts with the stearic acid to form a small amount of emulsified substance which still further lends smoothness and consistency to the entire mass.

The function of the waxes in the preparation is to form a thin film on the area to be shaved, which film aids in forming a mechanical support to hold the hair upright so that the razor will cut and not pull through the hair. The menthol and camphor are employed for their local anæsthetic effect in sufficient quantities to stimulate the nerves by accentuation of the sense of perception of cold. Thus, a cooling and pleasing effect is obtained by the use of these substances. The perfumes are added in small amounts to render a lasting effect that remains on the face long after the shaving operation is completed. The water which is introduced with the boric acid is essential to the consistency of the cream.

As stated above, the proportions of the ingredients, as well as the ingredients themselves, may be varied. For example, instead of using

stearic acid for the base, an equivalent amount of a similar fatty acid, such as palmitic acid, may be substituted. Numerous vegetable oils having substantially the same melting point as cocoanut oil, may be employed instead of the latter. The paraffin and spermaceti waxes may be used singly or in combination, or other waxes of approximately the same melting point may be employed. However, for best results the use of spermaceti and paraffin wax in the proportions named, 10 should be adhered to. The boric acid may be dispensed with and, if desired, other suitable alkali borates such as potassium or ammonium borate may be used.

In place of ammonium hydroxide, there may 15 be employed the chemical equivalent of one or more derivatives or amines. The perfumes employed are discretionary.

The resulting preparations can be used if desired by direct application to the face without 20 previous treatment. The resulting shave is easy and nonpulling, leaving the face soft and smooth. The cream remaining on the face after shaving may, if desired, be rubbed into the skin in order that the same may obtain the beneficial properties of the antiseptic and softening ingredients contained therein. The cream may, however, be washed off in either cold or hot water. Irrespective, however, of the details of use of the cream, 25 the essential features of the invention are always 30 preserved.

The invention is not to be limited to the exact compositions set forth in this application, as various changes in the proportions and in the ingredients involved may be resorted to without departing from the spirit of the invention. Only 35 insofar as the invention has particularly been pointed out in the accompanying claim, is the same to be limited.

What we claim as new and desire to secure by Letters Patent is:

A neutral shaving preparation of a latherless type which consists of a mixture of the following ingredients in substantially the proportion stated, 45 stearic acid 11 grams, lanolin 10 grams, cocoanut oil 0.3 gram, concentrated ammonium hydroxide 1.35 grams, paraffin wax 6 grams, spermaceti wax 2 grams, boric acid 1.5 grams, water 75 grams, and having a trace each of menthol, camphor and 50 perfume.

GEORGE D. GETTEMULLER.
